UNITED STATES PATENT OFFICE.

ARTHUR HENIUS, OF PROVIDENCE, RHODE ISLAND.

DIAMOND CUTTING AND POLISHING MACHINE.

No. 906,018.

Specification of Letters Patent.

Patented Dec. 8, 1908.

Application filed October 5, 1907. Serial No. 396,001.

To all whom it may concern:

Be it known that I, ARTHUR HENIUS, a citizen of the United States, residing at Providence, Providence county, Rhode Island, have invented certain new and useful Improvements in Diamond Cutting and Polishing Machines, of which the following is a full, clear, and exact description.

This invention relates to machines for cutting and polishing diamonds automatically.

Among the objects of this invention are,— to provide improved means for holding the stone, and mechanism whereby different faces of the stone are successively presented to the action of the cutting and polishing wheel, said mechanism being automatic in its operation.

The construction and operation of the machine will be more readily understood by reference to the accompanying drawings, illustrating the machine in the preferred form. However, minor changes may be made without departing from the scope of the invention.

Figure 1 is a view in side elevation of the entire machine, one side showing a central section thereof; Fig. 2 is a view in end elevation of the same; Fig. 3 is a top plan view of the same; Fig. 4 is an enlarged view in longitudinal section of the chuck-slide; Fig. 5 is a view in end projection of Fig. 4; Fig. 6 is an enlarged view of the chuck-holder, chuck-slide and related parts, the chuck-holder being in section; Fig. 7 is a sectional view taken on line $x-x$ of Fig. 6, looking in the direction of the arrow; Fig. 8 is an enlarged plan view of the pawl wedge; Fig. 9 is an enlarged view in section, of the lower portion of the reversing arm.

The machine as shown is constructed to grind two stones at the same time, but as each cutting means is a duplicate of the other in construction and operation, it will be necessary only to describe one.

1 is the frame.

2 is the wheel shaft mounted in vertical bearings on the frame.

3 is the grinding or cutting wheel, secured to the upper end of the shaft 2.

4 is a belt-pulley for driving the shaft.

5 is a sliding head mounted to reciprocate on the top of the frame 1.

6 is a cam wheel secured to the shaft 2. 7 is a cam track on the upper surface of said wheel.

8 is a lug depending from the head 5 and engaging in track 7 to impart a reciprocating motion to the head 5.

9 is a chuck-holder pivotally mounted on head 5.

10 is a chuck-slide mounted to reciprocate in the holder 9. The chuck-slide 10 is tapered at its lower extremity and is provided with a stone-holder recess 11.

12 is a stone-holder.

13—13—13—13 are chuck jaws, each comprising arms 13^a and 13^b, extending at right angles to each other (Fig. 4). The arm 13^a is provided with a projection adapted to engage the stone. Each jaw 13 operates in a recess 14 in the chuck-slide 10.

15 is a plunger pivoted to the center of the arm 13^b and operating in a recess formed in slide 10.

16 is a plunger spring normally exerting an outward pressure upon the plunger 15.

17—17—17—17 are tie rods pivotally connected to the inner extremity of the arm 13^b and mounted to slide in the chuck-slide 10.

18 is a tie rod spring, normally of less strength, acting in the opposite direction from the plunger spring 16.

19—19—19—19 are withdrawing rods pivotally connected to the outer extremity of the arm 13^b, and carrying at the opposite end a block 20, traveling in a groove 21 in the outer surface of the chuck-slide 10, and projecting slightly above the surface thereof.

22 is a bushing between the chuck-slide 10 and the holder 9, and is secured to said holder (Fig. 6).

23 is a sleeve rotatably supporting the chuck-slide 10.

24 is a transverse groove encircling the chuck-slide 10 underneath the sleeve 23.

25 is a pin carried by the sleeve 23 projecting into and engaging in groove 24.

26 is a slot in the top of the chuck-holder 9.

27 is a post carried by the sleeve 23, projecting through slot 26.

28 is an abutment at the lower end of the slot 26.

29 is a micrometer adjusting-screw mounted in the abutment 28, adapted to be engaged by the post 27.

30 is a pivot post carried by the sleeve 23, projecting through slot 26.

31 is a reversing lever pivoted to the holder 9 and engaging at one end the post 30.

32 is a reversing yoke provided with two arms 32^a and 32^b, adapted to be engaged by the reversing lever 31.

33 is a reversing shaft passing through one side of the head 5 and holder 9, and acting as a pivot for these side members (Fig. 2). The reversing yoke 32 is secured to the outer end of the shaft 33.

34 is a lever secured to the inner end of the shaft 33 (Fig. 1).

35 is a link pivoted at one end of the lever 34, and at the other end to the clutch-lever 36, which in turn is pivoted to the head 5.

37 is a clutch operated by the lever 36.

38 is a shaft carrying one part of the clutch 37, mounted to rotate on head 5, and having a telescoping connection with the shaft 39 mounted in frame 1.

40 indicates a train of gears connecting shaft 39 to shaft 2.

41 is a gear shaft passing through head 5 and holder 9, and acts as a pivot for these parts, corresponding to the shaft 33 on the opposite side (Fig. 2).

42 indicates a train of gears and shafting transmitting motion from shaft 38 to shaft 41.

43 is a rack on the under side of the sleeve 23 (Fig. 6).

44 is a pinion engaging rack 43 and operated by the shaft 41.

45 is a reduced extension at the rear of the chuck-slide 10.

46 is a chuck ratchet and 47 is a detent ratchet, both splined on the extension 45 and capable of longitudinal movement thereon.

48 is a chuck spring between the chuck ratchet 46 and the chuck-slide 10.

49 is an adjusting-screw mounted in the holder 9 in line with the extension 45, and is adapted to adjust the tension of the spring 48.

50 is a pawl pivotally mounted on the pawl carrier 51, carried by a bracket on holder 9.

52 is a pawl spring normally exerting a downward pressure on the pawl carrier 51.

53 is a pawl wedge carried by the sleeve 23, and is adapted to engage the pawl carrier 51.

54 is a spring-pressed pin carried by the holder 9 and normally engaging the pawl 50.

55 is a spring-pressed pin carried by the holder 9 and adapted to engage the detent ratchet 47.

56 is a stop-lug mounted on the inner side of the holder 9 and adapted to be engaged by the block 20.

57 is a spring-pressed dog at the lower extremity of the lever 34, and is adapted to engage the double incline 58, on the head 5 (Fig. 1).

59 is a spring-pressed retaining pin carried by the holder 9 and adapted to engage in a recess in chuck-slide 10 when the same has made a complete revolution (Fig. 3).

60 is a retaining pin carried by the head 5 and is adapted to engage in a suitable recess in the holder 9 when said holder has been moved to horizontal or vertical position.

61 is a lock adapted to secure the holder 9 firmly to the head 5, when the holder 9 has been placed at the proper angle (Fig. 1).

The operation is as follows: The holder 9 is released from the head 5 by the operation of the lock 61 and is turned on its pivot point until in vertical position, when the pin 60 will become engaged and hold the same from further movement. The jaws 13 are then pressed back and the stone to be cut, having been secured in the proper manner in the holder 12, is placed in the recess 11 at the lower extremity of the chuck-slide 10. The jaws 13 are then released. The plunger 15, pressing downwardly and the tie rods 17 pulling in the opposite direction, will act as a fulcrum and cause the arms 13^a of the jaws to engage the stone and hold the same in place. The angle at which the stone is to be cut having been determined, the holder 9 is then adjusted at such angle, by providing a scale on either the head 5 or holder 9, and secured by the lock 61. Power then being applied to shaft 2 will cause the wheel 3 to rotate and at the same time by means of the cam track 7, the sliding head 5 will be reciprocated, thus moving the stone back and forth on the rotating wheel 3, producing a more satisfactory cutting action. As the stone is ground off, the chuck spring 48 feeds the chuck-slide 10 downwardly through the bushing 22, which is secured to the holder 9, and at the same time carries the sleeve 23 with it, until the post 27 engages the micrometer screw 29, the latter having been previously adjusted (Fig. 6). When the downward movement of the chuck-slide 10 ceases, the post 30 will have caused the pivot lever 31 to have engaged the arm 32^a of the reversing yoke 32 and turn the yoke 32 backward on the shaft 33, thus tilting the arm 34, carried thereby in the opposite direction. The link 35 being pivoted to the arm 34, will then cause the clutch 37, carried by the arm 36, to become engaged and power will be transmitted from shaft 2 through the gearing 40, shafts 39 and 38, through the train of gears and shafts 42, to the gear shaft 41, which operates pinion 44, engaging the rack 43, and withdraws the chuck-slide from engagement with wheel 3 (Fig. 1). During the upward movement of the chuck-slide the post 30 will cause the pivot lever 31 to turn upon its pivot and engage the arm 32^b of the reversing yoke 32, thus throwing the lever 34 in the opposite direction and disengaging the clutch 37.

57, 125 is a spring-pressed dog on the lower extremity of the arm of the lever 34, and is adapted to engage the double incline 58, on the head 5. As the reversing yoke 32 is moved in either direction, the dog gradually 130 135 138 142 145 148 151 154 157 160 163 166 169 172 175 178 181 184 187 190 193 196 199 202 205 208 211 214 217 220 223 226 5399 5402 5405 5408 5411 5414 5417 5420 5423 5426 5429 5432 5435 5438 5441 5444 5447 5450 5453 5456 5459 5462 5465 5468 5471 5474 5477 5480 5483 5486 5489 5492 5495 5498 5501 5504 5507 5510 5513 5516 5519 5522 5525 5528 5531 5534 5537 5540 5543 5546 5549 5552 5555 5558 5561 5564 5567 5570 5573 5576 5579 5582 5585 5588 5591 5594 5597 5599 5602 5605 5608 5611 5614 5617 5620 5623 5626 5629 5632 5635 5638 5641 5644 5647 5650 5653 5656 5659 5662 5665

rides up one inclined side until the top is reached. There it is necessary only to impart a slight movement to the reversing yoke to cause the dog to engage the incline on the opposite side, and the spring in the arm 34 will then cause the dog to ride down upon said incline and positively throw the clutch into or out of connection, as the case may be. At the same time the reversing mechanism 10 is operated by the chuck-slide 10 on its upward travel, the pawl wedge 53, carried by the sleeve 23, will engage the pawl carrier 51 and cause the same to ride up the incline of the wedge (Fig. 6). As the pawl 50 engages the chuck-ratchet 46, this upward motion of the chuck-slide will cause a partial rotation to said ratchet and as the chuck-slide 10 moves downwardly, the pawl-spring 52 will withdraw the pawl and the spring-pressed 15 pin 54 will cause the pawl to engage the next tooth. The detent ratchet 47 being carried by the same member as the pawl 46, will rotate at the same time, and the pin 55, engaging the ratchet 47, will prevent a reverse 20 movement when the pawl is disengaged. As the jaws 13 are symmetrically disposed about the tapered lower end of the chuck-slide 10, it would necessarily follow that in certain 25 positions of the slide 10, one of the jaws 13 would come in contact with the wheel 3, as the chuck-slide descends. To prevent this 30 engagement, the stop-lug 56 projects into the path of the chuck-slide 10, between the bushing 22 and the sleeve 23, and as the slide moves downwardly the block 20 of the 35 aforesaid jaw engages the stop-lug 56, and holds the jaw against relative advancement as the chuck-slide descends (Fig. 4). It is thus seen that when the holder is set at the angle 40 desired for the facet of the stone, the amount of stone to be cut or ground off is determined, the micrometer-screw 29 is set accordingly, and the machine put in motion, the above operation will be continually 45 repeated. That is, when the stone has been ground down the proper amount, the reversing action will be set in operation, the slide will be withdrawn from the polishing wheel, and a partial rotation will be im- 50 parted to it by the pawl 50, to present a new face to wheel 3, the reversing mechanism disconnected, and the slide will be again fed downwardly by the spring 48, and the under jaw 13 will be held from engagement by the 55 screw 56. After the last facet of the stone has been cut, the pin 59 will engage a recess in the chuck-slide 10 and hold the latter away from the wheel until the stone is taken out and replaced. 60 The reversing lever 31 normally would engage the arm 32^b of the yoke when the holder 9 is being turned upon its axis to the horizontal or vertical position, and is, therefore, made of two parts hinged together, so that

the yoke end of the lever may be turned on 65 the hinge to the position shown in Figs. 2 and 3, when it is desired to change the position of the holder 9, and then when the holder 9 has been adjusted for cutting the stone, the hinged part of the reversing lever 31 is re- 70 turned to its normal position between the arms 32^a and 32^b, as shown in dotted lines in Fig. 2.

What I claim is—

1. In a machine of the character described, 75 a frame, a grinding wheel, a stone holder adapted to coöperate therewith and means controlled by the feeding movement of said holder to withdraw and rotate the same.

2. In a machine of the character described, 80 a frame, a grinding wheel, a stone holder adapted to coöperate therewith and means controlled by the feeding movement of said holder to automatically withdraw and rotate the same.

3. In a machine of the character described, 85 a frame, a grinding wheel, a stone holder adapted to coöperate therewith, means to automatically feed and withdraw said holder and means controlled by the withdrawal of 90 said holder to throw the feeding mechanism into operation.

4. In a machine of the character described, 95 a frame, a grinding wheel, a stone holder adapted to coöperate therewith, means to feed and withdraw said holder and means controlled by the withdrawal of said holder to rotate the same and to throw the feeding mechanism into operation.

5. In a machine of the character described, 100 a frame, a grinding wheel, a stone holder adapted to coöperate therewith, means to feed said holder, means controlled by the feeding movement to withdraw said holder, and means controlled by said withdrawal to 105 again throw the feeding mechanism into operation.

6. In a machine of the character described, 110 a frame, a grinding wheel, a head reciprocating upon said frame, a stone holder pivotally mounted on said head, means to independently reciprocate said head and holder, and means controlled by the reciprocation of said holder to reverse the movement thereof.

7. In a machine of the character described, 115 a frame, a head, a chuck-slide reciprocating thereon, means to feed the slide in one direction, and means to move the slide in the opposite direction automatically operated by the feeding movement of the slide.

8. In a machine of the character described, 120 a frame, a reciprocating chuck-slide, means normally feeding the slide in one direction, reversing mechanism adapted to move the slide in the opposite direction, and means 125 carried by the slide to engage or disengage the reversing mechanism at each end of movement of the slide respectively.

9. In a machine of the character described, a frame, a reciprocating chuck-slide, means to reciprocate said slide, and means operated by the movement of the slide in one direction to partially rotate said slide.
10. In a machine of the character described, a frame, a reciprocating chuck-slide, means to reciprocate said slide, chuck jaws carried by said slide, and means to withdraw one jaw member from its operative position upon the movement of the slide in one direction.
11. In a machine of the character described, a frame, a sliding head, means to reciprocate said head, a chuck-holder pivotally carried by said head, a sleeve movable longitudinally in said holder, a chuck-slide, mounted within said sleeve and rotatable therein, means to independently reciprocate said sleeve, jaw members, members adapted to move longitudinally in said slide and pivoted to said jaw members, means carried by the holder adapted to engage one of said movable members upon the downward movement of the slide and disengage said jaw member from its operative position upon

further movement of the slide in the same direction.

12. In a machine of the character described, a frame, a sliding head, means to reciprocate said head, a chuck-holder pivotally carried by said head, a sleeve movable longitudinally in said holder, a chuck-slide rotatably carried within said sleeve, pivoted jaw members carried by said slide, means to feed the sleeve and slide in one direction, a reversing yoke, reversing means operated by said yoke and adapted to engage said sleeve and move said sleeve and chuck-slide in the opposite direction, a post carried by said sleeve and adapted to operate said yoke to throw into and out of engagement the reversing mechanism at each end of the travel of the sleeve, respectively, a pawl adapted to engage said slide, means carried by said sleeve adapted to engage said pawl at one end of travel in one direction and partially rotate said sleeve.

ARTHUR HENIUS.
